(57) **CLAIM**

We claim the ornamental design for a charger for a electric device, as shown and described.

DESCRIPTION

FIG. 1 is a front perspective view of a charger for an electric device showing our new design;

FIG. 2 is a rear perspective view thereof;

FIG. 3 is a front view thereof;

FIG. 4 is a rear view thereof;

FIG. 5 is a side view thereof;

FIG. 6 is a top view thereof; and,

FIG. 7 is a bottom view thereof.

The broken lines shown in the drawings are included for the purpose of illustrating environmental structure and form no part of the claimed design.
